Primary Examiner — Sandra Snapp(74) Attorney, Agent, or Firm — Quarles & Brady LLP(57) CLAIM

The ornamental design for a seat portion, as shown and described.

DESCRIPTION

FIG. 1 is a left, top, front perspective view of a seat portion according to our new design, the bottom thereof is unseen in use;

FIG. 2 is a top, rear perspective view from the left side thereof;

FIG. 3 is a front elevational view thereof;

FIG. 4 is a rear elevational view thereof;

FIG. 5 is a left side elevational view thereof; and,

FIG. 6 is a top plan view thereof.

The broken line representations in the figures are for the purpose of illustrating unclaimed boundaries. The broken lines are thus not part of the claim.
